REVOLUTION-COUNTER RESETTING.

1,400,197.

Specification of Letters Patent. Patented Dec. 13, 1921.

Application filed September 30, 1920. Serial No. 413,792.

To all whom it may concern:

Be it known that I, ANDREW C. Wood, a citizen of the United States, and a resident of the city of Chicago, in the county of Cook and the State of Illinois, have invented certain new and useful Improvements in Revolution-Counter Resetting, of which the following is a specification, reference being had to the accompanying drawings forming a part thereof.

The purpose of this invention is to provide a suitable construction of revolution counter adapted for resetting to zero or any other identical figure alinement, or for resetting unit-by-unit from a higher to a lower reading or vice versa, both operations to be performed by the same manually operable part. It consists in the elements and features of construction shown and described as indicated in the claims.

In the drawings:

Figure 1 is a partly sectional front elevation of a portion of the counter train of the device embodying this invention, section being made axially with respect to the main counter shaft and the resetting shaft through part of the elements of the train.

Fig. 2 is a section at the line, 2-2, on Fig. 1.

Fig. 3 is a section at the line, 3-3, on Fig. 1.

Fig. 4 is a section at the line, 4-4, on Fig. 1.

Fig. 5 is a section at the line 5-5, on Fig. 1.

Fig. 6 is a sectional view similar to the sectional portion of Fig. 1, showing the parts adjusted to a position for resetting.

The structure shown in this application embodies an improvement on the substance of my pending application No. 375,515, filed April 21, 1920, for a device of the same general class and type. In the said pending application the construction shown is adapted for resetting all the dials at once by a single shift or revolution in one direction of the main shaft, and the lowest denomination dial, to zero or to any other identical figure alinement, and also for setting to any numeral indication unit-by-unit from zero or any lower reading to any higher reading, the same manually operable parts, as

a rotatable knob, serving for both features of resetting.

In that construction no means is provided for resetting unit-by-unit downward,—that is, from a higher to a lower reading. In the present application, the structure shown is adapted also for setting from higher to lower reading, unit-by-unit, the same manually operable part serving for that mode of resetting, and also for resetting all the wheels at once to zero or any other identical figure alinement.

In said former pending application the resetting unit-by-unit from zero being effected by manual operation of the train as it is operated in the normal running when driven by the shaft whose revolutions are to be counted, it is evident that the manual operation must be by rotation of the main shaft or prime rotated element of the train in the same direction as it is rotated in the normal running; and from this it follows that the other setting,—to zero or other identical figure alinement—must be by rotation in the opposite direction.

In the structure of the present application, the setting unit-by-unit downward,—that is, from a higher to a lower reading,—being effected by the rotation of the main shaft or prime rotated element of the train, it is evident that it must be done by the rotation of that prime element in the reverse direction from that in which it is rotated in the normal running. And it follows that if this is to be done by the same manually operated part which is employed for resetting all the wheels simultaneously to zero or other identical figure alinement, the latter adjustment must be effected by rotating the shaft in the opposite direction,—that is, in the direction of normal running of the shaft.

To this end, the construction is as follows.

The mount or frame structure for the device comprises a main frame member, 1, bearing brackets, 2 and 3, mounted thereon, and a housing member, 4, which incloses the intermeshing gears and the parts of the manually operating resetting device. The counter train main shaft, 5, is journaled in the brackets, 2 and 3, and its right hand end extends into the housing, 4, in which there is journaled the reset shaft, 6, extending out-

side the housing for carrying a knob, 6^a, by which it is manually operated. On the end of the shaft, 5, within the housing, 4, is a beveled gear, 7, which meshes with a larger beveled gear, 8, on the reset shaft, 6, when the said shaft is longitudinally adjusted to the proper position for intermeshing of said gears. At the running position of the counter-train the last two gears are not in mesh, 10 but instead the shaft, 5, is stopped in an annular groove, 6^a, of the shaft, 6, having one side sloped out to a greater diameter to the margin of a lesser groove, 6^b, and thence further sloped to the margin of still shallower groove, 6^c, in the shaft, the two lesser grooves being adapted for stopping the shaft, 5, at two different longitudinal positions for the purpose hereinafter explained. When the reset shaft, 6, is pulled out by the 20 knob, 6^a, for taking the end of the shaft, 5, in the shallowest groove, 6^c, said shaft, 5, is thereby thrust longitudinally inward with respect to the counter train against the reaction of a spring, 9, contained in an axial bore of the continuous train shaft, 10, which is aligned with the shaft, 5, and operates the continuous or totaling train of which two 25 dials are shown in Fig. 1, and which is driven in a manner entirely familiar and not requiring further explanation here and which constitutes no part of the present invention. On the main shaft, 5, it carries rigid therewith for rotation a gear, 12, which meshes with a driving gear, 13, which may be understood to be driven by the shaft whose revolutions are to be counted, the two gears being in the same plane transverse to the shaft, 5, at the position of said shaft shown in Fig. 1, that is, with its right hand end seated in the deepest groove, 6^a, of the reset shaft. When the shaft, 5, is thrust to the other position indicated—that is, for seating at its right-hand end in the shallowest groove, 6^c, of the reset shaft, the gear, 12, 40 is thereby carried out of the plane of the driving gear, 13, and therefore out of driving engagement with the shaft whose revolutions are to be counted, and free to be rotated for manual resetting by the reset shaft, 45 6, through the intermeshing bevel gears, 7 and 8. The construction, as thus far described, except as to the intermediate groove, 6^b, is substantially that of my copending application No. 375,515, and also my previous 50 application still pending, No. 353,770, filed January 24th, 1920, and is no part of the present invention.

The successive dials and number wheels, 20, 21 and 22, from lowest to highest are connected from lower to higher by means of a continuously toothed or unmutilated gear, 25, whose teeth are in number multiples of ten, mounted on the side of each number wheel toward the next preceding number 55 wheel or dial, each dial or number wheel

having a mutilated gear, 26, and a delay or locking disk, 27, at the side toward the next succeeding dial or number wheel; the mutilated gear, 26, has means for driving engagement throughout one-tenth of its circumference, and the delay or locking disk, 27, is correspondingly cut away at the side toward the next succeeding number wheel or dial; and a pinion, 28, is provided journaled on a shaft, 29, parallel to the main counter train 70 shaft, said pinion being actuated by the toothed portion of the gear, 26, for rotating the adjacent gear, 25, and its dial through one-tenth of a revolution for each revolution of the preceding gear, 26, and its dial, 75 thus effecting "carrying" from column to column. This construction for "carrying" in all details which are not here described, is fully shown and described in my said copending application, and in itself constitutes 80 no part of the present invention and need not be further described here.

The shaft, 5, is reduced in diameter from its left hand end which telescopes within the shaft, 10, to a shoulder, 5^a, and it is further reduced, for so telescoping, from its left hand end back toward the right hand end to a shoulder, 5^b, the total extent of the intermediate diameter portion of the shaft between the two shoulders being the total 95 length of the counter-train, comprising all the counter wheels and the gears thereon. The shaft, 5, has a key-way, 5^c, extending longitudinally from the shoulder, 5^a, nearly to the shoulder, 5^b, said key-way being a 100 rectangular groove from the shoulder, 5^a, to a point within the lowest counter wheel, the remainder of length of the key-way being cut-away at one side, leaving only one abrupt side, 5^d, to form a ratchet shoulder, and the 105 other side sloping off, as seen in Figs. 3, 4 and 5, so that any tooth adapted to engage said shoulder will operate as a pawl for one-way engagement with the shaft. 30 is a sleeve which serves as a bushing for the 110 lowest denomination counter-wheel or dial, and the delay and locking disks, 26 and 27, thereof. This bushing sleeve is reduced in exterior diameter at the end opposite the delay and locking disks, to seat a disk, 31, 115 which has the central aperture to fit the reduced end of the bushing sleeve, and a tooth, 31^a, projecting into its central aperture for engagement with a notch in the reduced end of the bushing and protruding therethrough 120 for engaging with the key-way, 5^c, in the shaft. The width of the central opening of the disk, 31, from the point of the tooth, 31^a, to the opposite side of the aperture is as great as the diameter of the shaft between 125 the shoulders, 5^a and 5^b. The parts mentioned are assembled by first passing the disk, 31, onto the shaft from the smaller end, the dimensions stated of the aperture in the disk permitting it to pass over the shoulder, 130

^{5^b}, notwithstanding the key-way is not cut through to the shoulder. The lowest denomination dial, 20, and its disks, 26 and 27, are then assembled on the bushing sleeve, 6, and the entire assembly is passed onto the shaft, and the disk, 31, having its tooth, 31^a, now engaged in the key-way, 5^c, is passed onto its seat on the reduced end of the bushing sleeve. The lowest denomination dial or 10 number wheel, 20, is secured fast to the disk, 31, and is kept in rotative engagement with the bushing sleeve by the tooth, 31^a, of the disk engaging its notch, 30^a, as described. On the shaft, 5, extending from the shoulder, 15 5^a, to the inner end of the sleeve, 35, within the whole axial extent of the number wheels above the lowest denomination is a second sleeve, 35, which is loose on the shaft for all purposes at all times, except as engaged therewith by the pawl and ratchet device 20 hereinafter described. The dials or number wheels, 21 and 22, of denominations above the lowest, are formed with their central sleeves or hub member, 21^a, rigid with them 25 and formed separately for convenience of assembling thereon the mutilated delay disks above described, and are mounted loosely on said sleeve for rotative engagement therewith by the pawl-and-ratchet devices 30 hereinafter described. On the inner end of the sleeve, 35, there is made fast by drive fit thereon, a disk, 36, on the face of which there is mounted a pawl, 37, and a spring, 38, for pressing the pawl onto the 35 shaft, 5, but without any engagement with that shaft at the normal running position, the key-way, 5^c, however, in said shaft 5, being extended so nearly to the plane of the left-hand side surface of the disk, 36, that 40 the longitudinal movement of the said shaft caused by the reset shaft, 6, when it is withdrawn so as to seat the right-hand end of said shaft in the shallowest groove, 6^c, of the reset shaft brings said key-way at the 45 end portion thereof, into the plane of said pawl for engagement of the pawl with the abrupt shoulder of said key-way. The sleeve, 35, has a ratchet-shaped key-way,—that is, having one abrupt shoulder and one 50 sloping shoulder or face, as seen at 35^a, extending along its entire length; and each of the number wheels or dials above the lowest denomination has mounted upon one face a pawl, 37, spring-pressed by a spring, 39, for 55 engagement of its free end with said key-way for one-way-driving connection between the sleeve and the number wheel or dial. Both the key-ways, 5^c, of the shaft, 5, and 35^a, on the sleeve, 35, have their abrupt 60 shoulders facing, and their respective pawls are mounted for driving engagement between the respective parts, in the same direction, and this direction is clock-wise direction of rotation of the shaft or sleeve as 65 viewed from the operating end at which the reset shaft is situated, being the direction of rotation of the shaft in the normal running of the counter train for registration of the revolutions of the shaft to be indicated.

The operation of the structures thus far described may be understood as follows:—

In the normal position for running to indicate the revolution of the shaft whose revolutions are to be counted, the reset shaft and the main counter drive shaft, 5, are 70 relatively positioned as shown in Fig. 1, that is, with the right hand end of the shaft, 5, seated in the deepest recess, 6^a, of the reset shaft, 6, and the gears, 7 and 8, out of engagement with each other. In this relation 75 of the parts, it will be understood that the rotation of the part, 1, causes the counter-train to indicate the revolutions in the regular manner by carrying from each wheel of lower denomination to the next higher by 80 units. When it is desired to reset in either of the methods above described the knob, 6^a, of the reset shaft, 6, is pulled out to withdraw the reset shaft, 6, to a position at which the shaft, 1, is seated in the shallowest 85 groove, 6^c, of the reset shaft, and the shaft, 5, is thereby thrust inward for carrying the gear wheel, 12, out of mesh with the driving gear thereof. With the parts in this position, rotation of the knob, 6^a, in clock-wise 90 direction producing rotation of the shaft, 5, in anti-clockwise direction, will rotate the initial or lowest denomination dial, 20, in reverse direction of its numbering, and the carrying mechanism will similarly rotate 95 reversely each of the succeeding dials, unit by unit, so as to reduce the numerical indications, unit by unit, from whatever point may have been reached in its normal running back to any point at which the operator 100 desires to reset in the rotation in this direction. In this operation the pawl, 37, while standing in a plane which crosses the key-way, 5^c, of the shaft, 5, will not engage with 105 said shaft because it is traveling in its reverse or riding direction back over the abrupt shoulder of that key-way. Similarly, in this direction of rotation, each of the number wheels or dials above the lowest denomination will drag their pawls, 37^a, 110 backward over the abrupt shoulders of the key-ways, 35^a, of the sleeve, 35, and will therefore, not actuate said sleeve.

If, however, the operator desires to reset the train back to zero or to any other identical figure of alignment, he will rotate the knob, 6^a, in the reverse of clock-wise direction, thereby rotating the shaft, 5, in clock-wise direction. Rotating in this direction the shaft, 5, by means of the key-way, 5^c, 115 will engage the pawl, 37, of the disk, 36, and will thereby rotate the sleeve, 35, in the direction to cause the abrupt shoulder of the keyway, 35^a, to engage the pawls of the several numeral wheels or dials above the low- 120

est denomination, and thereby in one complete revolution of the shaft and sleeve, all of said numeral wheels will be picked up and carried together; and these pawls being similarly positioned, with respect to the numbers on the peripheries of the dials or number wheels, when they are all engaged by the shoulder of the keyway, will have similar numbers in alinement, whereby all 5 the numeral wheels can be brought to alinement, said pawls being situated the keyway, 5°, of the shaft, being situated with respect to the lowest denomination dial or number wheel, 20, so that the zero of said lowest 10 15 20 25 30 35 40 45 50 55 60 65 70 75 80 85 90 95 100 105 110 115 120 125 130 wheel is alined with the zero of the wheels of higher denomination when the pawls on said wheels are engaged with the ratchet shoulder of the sleeve, 35. The intermediate groove 6^b, on the reset shaft, 6, is provided for the purpose of adapting the structure for advancing the reading by resetting forwardly unit by unit as in the regular running of the train. For this purpose the gear, 8, is feathered in the reset 25 shaft, 6, by a pin, 8^a, set into the shaft and engaging a slot, 8^b, in the hub of the gear and a spring, 8^c, is provided reacting between the stop flange, 8^d, of a sleeve or collar, 8^e, (which is pinned to the shaft by the same pin 8^a) and the back of the gear for holding the gear yieldingly against it a shoulder, 6^f, on the shaft 6,—so that the shaft 6, being withdrawn to the point at which the end of the shaft, 5, seats in the intermediate groove, 6^b, and the gears, 7 and 8, are meshed—may be still further withdrawn to thrust the shaft, 5, farther inward and seats its righthand end in the shallowest groove, 6^c—the gears, 7 and 8, being still operatively meshed and not objectionably jammed by the relatively tight reaction of the spring, 8^b, also to permit the shaft, 5, to thrust the second step for seating in the groove, 6^c, without disturbing the gear, 7, from its meshing position, said gear, 7, is held on the shaft, 5, between a stop afforded by the key, 5^m, which engages it with the shaft for rotation, and a spring, 5ⁿ, on the shaft, 5, at the side of the gear, 7, toward the reset shaft on said spring being stopped on the shaft, 5, by a pin, 5^p. When it is desired to advance the counter wheels, unit by unit, to a certain higher numerical indication, the reset shaft is withdrawn to the intermediate position at which the shaft, 5, is seated in the groove, 6^b. In this operation, it will be seen that the shaft, 5, is thrust inward a distance insufficient to carry the lefthand end of the ratchet groove or keyway, 5^c, out into the plane of the pawl, 37, on the disk, 36, and said pawl is therefore without engagement with the shaft, 5, when it is rotated in clockwise direction by means of the reset knob and shaft and gear rotated in anti-clockwise direction by the op-

erator—and such rotation of the reset parts will operate the counter train as it is operated in the ordinary running—*i. e.* for advancing the numeral indication unit by unit.

It will be observed that with the shaft, 20, set in the position above described for advancing the reading unit by unit, resetting in the reverse order can be affected by rotating the knob, 6^a, in clock-wise direction; and it is therefore possible to make corrections back and forth, that is, for advancing or reducing the indication, with the parts set in this position.

I claim:—

1. In a revolution counter, in combination with a series of counter wheels for successive decimal denominations; a counter main shaft on which the counter wheels are carried; permanently engaged for rotating the wheel of lowest denomination; means for carrying from each wheel of lower denomination to the next higher, adapted to operate similarly in either direction of rotation; one-way driving means of which one part is rotatably carried by said counter main shaft, and the other part by the respective counter wheels for driving the counter wheels of higher denomination without intervention of the carrying means, directly by the rotation of the shaft, in the direction for counting upward; said part carried by the shaft being unengaged therewith for rotation at the normal running position of the shaft; manually operated means for shifting the shaft longitudinally for rotative engagement of said parts, and for rotating the shaft at such shifted position.

2. In the construction defined in claim 1, the shaft carried part for the one-way driving being a floating sleeve on the shaft which is out of engagement therewith at the normal running position of the shaft, and means for engaging the sleeve with the shaft at the longitudinally shifted position of the latter.

3. In the construction defined in claim 1, foregoing, the shaft carried part for the one-way driving being a floating sleeve on the shaft, and a forward-drive ratchet connection between the sleeve and the shaft, of which the shaft-carried part is out of engagement with the sleeve-carried part at normal running position of the shaft, and means for engaging the sleeve with the shaft at the longitudinally shifted position of the latter.

4. In the construction defined in claim 1 foregoing, a sleeve loose on the main countershaft, free from driving engagement therewith at the normal running position of said shaft and sleeve, said sleeve having one of the parts of the one-way driving connection mentioned for each of the counter wheels above the lowest; normally disen-

- gaged means for engaging the shaft with said sleeve and means for shifting the shaft out of normal running position to effect the engagement of said normally disengaged means.
5. In the construction defined in claim 1 foregoing, a sleeve loose on the main countershaft, free from driving engagement therewith at the normal running position of the shaft and sleeve, said sleeve having one of the parts of the one-way driving connection mentioned for each of the counter wheels above the lowest denomination; one-way driving means normally disengaged for engaging the shaft with said sleeve, and means for shifting the shaft out of normal running position to effect the engagement of said normally disengaged means.
6. In the construction defined in claim 1 foregoing, means by which the shaft is normally in driven connection with the parts whose revolutions are to be counted, the said driving connections being adapted to be disengaged by the shifting of the shaft mentioned.
7. In the construction defined in claim 1 foregoing, means by which the shaft is normally in driven connection with the parts whose revolutions are to be counted, the manual means for rotating the counter main shaft being shiftable into and out of driving engagement with said shaft, the means for such shifting being adapted also to shift the counter main shaft out of and into its said shifting position.
8. In the construction defined in claim 1, the shaft-carried part for the one-way driving being a floating sleeve on the shaft which is out of engagement therewith at the normal running position of the shaft, and means for engaging the sleeve with the shaft at the longitudinally shifted position of the latter; the shaft being adapted to be shifted through two steps to two different positions, and to be unengaged with the sleeve at one of said shifted positions; the manually-operable means for rotating the shaft being operatively engaged at both said shifted positions.
9. In a revolution counter, in combination with a series of counter wheels for successive denominations, means for rotating the wheel of lowest denomination; means for carrying from each wheel of lower denomination to the next higher, adapted to operate similarly in the opposite-direction of rotation for carrying downward from each higher denomination to the next lower; said means comprising a main counter shaft on which the counter wheels are carried, and means by which it is normally in driven connection with the shaft whose revolutions are to be indicated; a reset shaft; gears on said main and reset shafts which are out of mesh at the normal running position of the mechanism; the reset shaft being manually movable for meshing with said gears; means by which said movement of the reset shaft actuates the counter main shaft for disengagement of its driven connection with the indicator shaft; one-way driving connections between the counter main shaft and the counter wheels above the lowest denomination, comprising a floating sleeve on the counter main shaft, which is out of engagement therewith at the normal running position of said shaft; the reset shaft means for actuating the counter main shaft being adapted for shifting said counter main shaft through two steps to two positions away from the normal, the sleeve being unengaged with the counter main shaft at one of said shifted positions, and means for one-way driving sleeve with the shaft which are brought into operative relation by the shifting of the shaft to the other of said two shifted positions.

In testimony whereof, I have hereunto set my hand at Chicago, Illinois, this 13th day of September, 1920.

ANDREW C. WOOD.
